AUTOMATIC SEDIMENT PURGER FOR TUBE
ICE MACHINESHenry V. Heuser, Louisville, Ky., assignor to
Henry Vogt Machine Company, Louisville, Ky.,
a corporation of Kentucky

Application May 29, 1950, Serial No. 164,875

4 Claims. (Cl. 62—107)

1

The present invention relates to ice-making machines, and relates in particular to an automatic sediment purger for clearing the water of sediment precipitated out by the freezing operation.

In machines of the tube type water is introduced into a supply tank through a level-controlled valve, and from the tank the water is pumped to the tops of the ice tubes of the freezer. Part of the water flowing down through the tubes is frozen and remains in the tubes, and the excess water, cooled to near freezing by its passage through the freezer, is returned to the tank. The freezing action concentrates the mineral content in the water returned to the tank to the point where the mineral content precipitates out. As water is being continuously added to replenish the water removed by freezing, this mineral sediment builds up to a quantity which is objectionable, because of the possibility that the sediment may circulate with the water and become frozen into the ice. Heretofore it has been necessary to manually drain and clean the supply tank at intervals to remove this sediment. This requires the attention of an operator, and also has the disadvantage that during intervals between cleaning there may be some sediment frozen into the ice.

It is an object of the present invention to provide for automatic removal of sediment from the supply tank, so as to prevent the sediment accumulating and circulating with the water to be frozen.

In accordance with the present invention, the supply tank is constructed with a low point or sump to which sediment tends to gravitate, and an overflow conduit is connected to the tank at this low point. A level-controlled inlet valve is adjusted so that during the freezing cycle it will maintain a liquid level slightly below the overflow level but high enough so that when the pump is stopped at the end of each freezing cycle and the water in suspension in the circulating system is returned to the supply tank, the overflow level is exceeded in the tank and water is discharged from the tank through the overflow pipe connection at the sump. As the overflow pipe is connected to the low point or sump in the tank, the escape of water carries along a substantial part of the sediment, thus removing it from the tank. Thus, the purging of the water tank automatically occurs at the end of each freezing cycle, without draining the whole tank.

The invention will be explained in greater detail in the following description taken in con-

2

nection with the accompanying drawing illustrating a preferred embodiment of the invention by way of example, and wherein:

Figure 1 is a side view, partly in section, of a tube ice freezer incorporating the invention;

Figure 2 is a front view in section of the water supply tank and overflow; and

Figures 3 and 4 are elevation views similar to Figure 2 of modifications.

Referring to the drawing, there is shown a conventional freezer 1 of the tube type, which may comprise a jacket 2 for containing a refrigerant surrounding water tubes 3, and through which tubes flows water or other liquid to be frozen. At the end of the freezing cycle a hot fluid is introduced into the jacket to thaw loose the solidified ice rods in the tubes, and the tubes are cut or broken by a severing device 4, the pieces being deflected by a baffle 5 to a grid 6 from which they fall to a storage bin 7. A water supply tank 8 is located below the grid, and a pump 9 draws water from the tank to a distributing chamber 11 at the top of the freezer, from which the water is distributed to the tubes. Excess water flowing through the tubes passes through grid 6 back to the tank 8.

A float 12 or other automatic level-controlled device operates an inlet valve 13 for the water tank to admit sufficient water to maintain a substantially constant level of water in the tank. By this arrangement, as the water level in the tank drops due to loss of water by freezing in the tubes, the replacement water is added. The excess water returned to the tank becomes chilled in its passage through the ice tubes so that the water supplied to the distributing chamber 11 at the tops of the tubes is close to the freezing point. The tank 8 has a sloping bottom 14, and at its lowest point there is connected a pipe which serves as an overflow and drain pipe. The overflow pipe 15 extends upward and has a bend 16 at or above the operating level of water in the tank, and the drain pipe 17 is normally closed by a valve 18. Because the overflow pipe 15 is connected at the low point of the tank, sediment will gravitate to this point, and at each overflow the sediment will be flushed out the overflow pipe.

The operation of the invention now will be explained. The ball float 12 tends to maintain the level of water in the tank 8 between a minimum and maximum level, and the overflow pipe 15 is set so that the bend 16 lies above the maximum level thus maintained in the tank, at which level the valve 13 is shut off by the float. As

suming the water level to be at the overflow, indicated by the dot-and-dash line O—O, when the pump is started the liquid level falls because of the water which is circulating through or is in suspension in the freezer and piping. The float 12 is set so as to open when the liquid level, indicated by the line M—M, falls below a predetermined minimum. The capacity of the tank between the levels M—M and O—O is less than the volume of the water in circulation or suspension in the system. Thus, when the pump is shut off and the water in suspension is returned to the tank the overflow level is reached before all the water has returned, so that a volume of water equal to the rest of the water will escape through the overflow and carry with it the precipitate accumulated in the tank. The amount of water purged in this way from the system is predetermined by the following formula: volume of water in tank at average level during operation plus water in suspension, minus the volume of water at overflow level, equals the purged water. Thus, by setting the overflow level and the float level as required, the desired amount of water may be purged each time the pump stops, varying from zero for lowest setting of the float ball to a maximum which is the volume of water held in suspension during the freezing period. Because the pump is shut off at the beginning of each thawing cycle, the sediment is automatically purged from the supply tank at such intervals.

In the modification shown in Figure 3 wherein like parts are designated by like reference numerals, the drain pipe 17 connects to the bottom of the tank and is provided with an inverted U-tube 21 vented at the top at 22. This arrangement operates in the same way as that shown in Figure 2, and has the additional advantage that the drain pipe 17 serves to carry away the overflow from pipe 21, thereby eliminating the additional pipe required in Figure 2. The vent 22 at the top prevents the development of a siphoning action after the overflow starts. Valve 18 ordinarily is closed and is opened to drain the tank.

In the modification shown in Figure 4 an inverted U-shaped pipe 23 extends through the end wall of the tank and has its horizontal portion or bend 24 at the maximum water level. This eliminates the underneath connection provided in Figure 3 with a saving in headroom of several inches. The vent 22 is controlled by a valve 25 which normally is open. When the pump stops, the return to the tank of the water in suspension raises the level, and flow through pipe 23 commences when the overflow level O—O is reached. The device may be employed as a drain by closing valve 25 which results in a siphon action to drain the tank.

I claim as my invention:

1. In a tube ice-making machine: a freezer

providing tubes subject to alternate freezing and thawing temperatures and through which water to be frozen is passed; a water supply tank providing a low point to which sediment gravitates; means connected to a higher point in the tank for pumping water from the supply tank to the tops of the freezer tubes whereby during the freezing period a quantity of water is maintained in suspension; means controlled by the level of water in the tank for replenishing water in the tank to a predetermined level; means for stopping flow of water to the freezer tubes during the thawing cycle whereby the suspended water returns to the tank to raise the liquid level therein; and an overflow pipe having a bend positioned between said predetermined level and raised level connected to said low point of the tank to purge settled solids therethrough and to limit siphoning of water to the level of said bend.

2. In an ice making machine an enclosure subject to alternate freezing and thawing phases through which flows water to be frozen; a water supply tank providing a low point to which sediment gravitates; means connected to said tank for pumping water from the supply tank to said enclosure during the freezing phase whereby a quantity of water is maintained in suspension, and the water in suspension is returned to the tank during the thawing phase; an intermittent drain connected to said low point operative at a predetermined water level in the supply tank to drain water until a differential minimum level in the tank is reached; and a supply valve having level control means adjusted to maintain the maximum water level in the tank during the freezing phase in a range between below said predetermined level and a level no lower than said differential distance below said minimum level, so that said drain becomes operative upon return of the water in suspension to the tank.

3. A tube ice-making machine as specified in claim 2 wherein the intermittent siphon comprises an inverted U-tube having a valved connection between the legs of the U, and having an air vent in said bend to limit siphoning.

4. A tube ice-making machine as specified in claim 2 wherein the intermittent siphon comprises an inverted U-tube passing through a wall of the tank, and having a valved vent between the legs of the U to prevent siphoning in open position of the valve.
